BOILER

Kenneth N. Smith, Springfield, and August L. Oberbeck, Jefferson City, Mo.

Application August 26, 1949, Serial No. 112,576

2 Claims. (Cl. 122—149)

1

This invention relates to steam boilers, and more particularly to a steam boiler utilizing waste heat from the exhaust of an internal combustion engine, or the like.

A main object of the invention is to provide a novel and improved steam boiler operating from the exhaust heat from an internal combustion engine, said boiler being simple in construction, being easy to connect to a conventional internal combustion engine, and providing a great saving in fuel and utilization of heat which would otherwise be wasted.

A further object of the invention is to provide an improved steam boiler for use with an internal combustion engine, said boiler being inexpensive to construct, providing efficient utilization of the waste heat from the internal combustion engine, and providing a supply of steam derived from a source of heat which would otherwise be wasted.

Further objects and advantages of the invention will become apparent from the following description and claims, and from the accompanying drawings, wherein:

Figure 1 is an elevational view, partly in cross-section, showing an improved boiler according to the present invention installed in operating position with relation to a plurality of conventional internal combustion engines;

Figure 2 is a transverse vertical cross-sectional view taken through the boiler of Figure 1, showing one of the internal combustion engines in side elevation;

Figure 3 is a transverse vertical cross-sectional view taken on line 3—3 of Figure 1.

Referring to the drawings, 11 designates a plurality of conventional internal combustion engine units, such as engines of the diesel type, said units having exhaust manifolds shown at 12. The engine units have conventional water-cooling jackets having inlet conduits 13 and outlet conduits 14. The inlet conduits 13 are connected through respective valves 15 to a water supply pipe 16, the pipe 16 being connected to a source of water supply, not shown. The outlet conduits 14 are connected to a discharge pipe 17. Pipe 17 is connected through a pump 18 to a conduit 19. Designated at 20 is a vertical cooling tower containing a vertical discharge conduit 21, to the bottom end of which is connected the conduit 19. Adjacent its connection to the cooling tower, conduit 19 contains a check valve 22 allowing water to flow into the vertical conduit 21, but preventing reverse flow thereof. The water supply pipe 16 is connected to the lower portion of the cooling tower 20 immediately above the connection of conduit 19 thereto, as shown in Figure 1.

2

The structure thus far described is conventional. The cooling water is admitted to the engine-cooling jackets from pipe 16 through conduits 13 and leaves the engine jackets through conduits 14. The warmed water flows through pipe 17 and pump 18 to conduit 19, passes through check valve 22 into vertical pipe 21 and discharges from the top end of pipe 21 into the cooling tower 20. The cooled water at the lower portion of tower 20 enters supply pipe 16 to repeat the cooling cycle.

Designated at 23 is a horizontal boiler supported in any suitable manner adjacent the engine units 11. Boiler 23 comprises a cylindrical shell or body 24 having the end walls 25 and 26 secured thereto. End wall 26 carries the conventional sight tube 27. The bottom of shell 24 is provided with a drain plug 28. Connected to the boiler adjacent end wall 25 and extending through the top of the shell 24 is a vertical intake conduit or pipe 29, terminating adjacent the bottom of the shell. Connected to supply pipe 16 adjacent cooling tower 20 is a pipe 30 including a hand valve 31. The top end of pipe 30 is connected to conduit 29 through a float-operated valve 32. Valve 32 is actuated by a float member 33 located in the upper portion of boiler 23 and connected in a conventional manner to the operating mechanism of valve 32. The float member 33 closes valve 32 when the level of water in boiler 23 rises beyond a predetermined value. When the level of water falls below this value, float 33 opens valve 32 and allows water to enter the boiler.

A steam discharge conduit 34 is connected to the top of boiler shell 24 through a hand valve 35. Also connected to the top of boiler shell 24 are a steam pressure gage 36 and a conventional safety valve device 37 of the blow-off type.

Mounted inside boiler 23 is a hollow core 38 comprising a main cylindrical body 39 extending coaxially with respect to the boiler. Body 39 is formed with end walls 40 and 41, and connecting said end walls are a large number of tubes 42. End wall 41 is formed with an annular enlarged shell portion 43. Secured to the edge of shell portion 43 is a circular end plate 44, an asbestos gasket 45 being interposed between plate 44 and said edge. End wall 43 has an outer flange 46, and secured to said flange is a cylindrical shell 47 provided with the circular end plate 48 and the asbestos gasket 49 interposed between plate 48 and the edge of shell 47. The space in shell portion 43 communicates with a conduit 50 extending through the lower portion of hollow core 38. The space in shell 47 communicates with a conduit 51 extending through the upper portion of core 38. The ex-

haust manifolds 12 are connected through flexible hose sections 57, valves 58 and thermally-insulated conduits 52 to the lower conduit 59 in housing 38, said conduits 52 entering the lower wall portion of boiler shell 24 and having water-tight connections therewith. Connected to the upper conduit 51 are respective exhaust conduits 53, leading to the exhaust flue of the engines. The conduits 53 are interconnected by by-pass conduits 54, and the end conduit 53 is connected to a conduit 55 leading to the top wall portion of shell 43. A damper valve 56 is provided in conduit 55.

In operation, hollow core 38 is surrounded by the water in boiler 23. The hot exhaust gases flow upwardly into core 38 from the exhaust manifolds 12 of the engines 11, through conduits 52, and enter conduit 50. The hot gases flow through conduit 50 to the right, as viewed in Figure 1, and enter the space in shell 43. Part of the hot gases flows through the tubes 42 to the space in shell 47 and thence through conduit 51 to the exhaust conduits 53. The remaining portion of the hot gases flows through conduit 55 to said exhaust conduits. The proportion of the gases flowing through tubes 42 may be regulated by adjusting the damper 56.

By conducting the exhaust gases through conduit 50, tubes 42 and conduit 51, the exhaust gases are retained in the heat-exchange hollow core 38 for a length of time great enough to allow the gases to give up a substantial amount of heat to the water in boiler 23. Due to the relatively high temperature of the exhaust gases, the amount of heat transmitted to the water is great enough to elevate the temperature of the water to a sufficiently high value to generate steam at a substantial pressure. This steam is available at the outlet conduit 34. The supply of water in boiler 23 is constantly replenished from supply pipe 16 through pipe 30 and float valve 32.

While a specific embodiment of a boiler utilizing the exhaust heat of internal combustion engines has been disclosed, it will be understood that various modifications within the spirit of the invention may occur to those skilled in the art. Therefore, it is intended that no limitations be placed on the invention except as defined by the scope of the appended claims.

What is claimed is:

1. A boiler comprising a horizontally disposed closed ended hollow cylindrical body, a hollow closed ended cylindrical core disposed longitudinally of and within said body and spaced from said body, a vertically disposed closed shell arranged exteriorly of each of the closed ends of said core and secured thereto, a plurality of open ended tubes positioned longitudinally of and within said core and each having the open ends extending through the adjacent closed end of said core and in communication with the adjacent vertically disposed shell, a conduit extending longitudinally through said core adjacent the bottom thereof and having one end in communication with one of said vertically disposed shells, a plurality of spaced inlet conduits extending transversely through said body and in communication with said conduit for receiving hot gases, a second conduit extending longitudinally through said core adjacent the top thereof and having one end in communication with the other of said vertically disposed shells, a plurality of spaced outlet conduits extending transversely through said body and in communication with said second conduit for discharging hot gases, a vertically disposed intake pipe positioned within said body adjacent one end thereof and having the lower end spaced from the bottom of said body for introducing water into said body, a third conduit extending vertically from the top of said body intermediate its ends for discharging the steam therefrom, and a bypass conduit positioned exteriorly of said body and having one end connected to one of said outlet conduits and having the other end in communication with the top of said one of the vertically disposed shells.

2. A boiler comprising a horizontally disposed closed ended hollow cylindrical body, a hollow closed ended cylindrical core disposed longitudinally of and within said body and spaced from said body, a vertically disposed closed shell arranged exteriorly of each of the closed ends of said core and secured thereto, a plurality of open ended tubes positioned longitudinally of and within said core and each having the open ends extending through the adjacent closed end of said core and in communication with the adjacent vertically disposed shell, a conduit extending longitudinally through said core adjacent the bottom thereof and having one end in communication with one of said vertically disposed shells, a plurality of spaced inlet conduits extending transversely through said body and in communication with said conduit for receiving hot gases, a second conduit extending longitudinally through said core adjacent the top thereof and having one end in communication with the other of said vertically disposed shells, a plurality of spaced outlet conduits extending transversely through said body and in communication with said conduit for discharging hot gases, a vertically disposed intake pipe positioned within said body adjacent one end thereof and having the lower end spaced from the bottom of said body for introducing water into said body, a valve in said intake pipe, a float member in said body and operatively connected to said valve for controlling the admission of water into said body, a third conduit extending vertically from the top of said body intermediate its ends for discharging the steam therefrom, a bypass conduit positioned exteriorly of said body and having one end connected to one of said outlet conduits and having the other end in communication with the top of said one of the vertically disposed shells, and an adjustable damper valve in said bypass conduit for regulating the quantity of hot gases being bypassed.
